INVENTOR

Joseph W. Hobson
BY Franklyn
ATTORNEY

UNITED STATES PATENT OFFICE.

JOSEPH W. HOBSON, OF NEW YORK, N. Y., ASSIGNOR TO CARR & HOBSON,
(LIMITED,) OF SAME PLACE.

LAWN-MOWER.

SPECIFICATION forming part of Letters Patent No. 275,338, dated April 3, 1883.

Application filed November 21, 1882. (No model.)

To all whom it may concern:

Be it known that I, JOSEPH W. HOBSON, of the city, county, and State of New York, have invented a new and useful Improvement in 5 **Lawn-Mowers**; and I do hereby declare the following to be a full, clear, and exact description of the same, reference being had to the accompanying sheet of drawings, forming part of this specification.

10 This invention is in the nature of an improvement in lawn-mowers; and the invention is a lawn-mower, with the cutter thereof, consisting of two or more blades united by slotting them in the direction of their length and 15 inserting the slotted portion of one blade into the slotted portion of the other or others, in combination with suitable journals united thereto in any desirable manner.

20 In the accompanying sheet of drawings, Figure 1 is a plan or top view of my improved cutter and lawn-mower. Fig. 2 is a cross-section taken in line *x*, Fig. 1. Figs. 3 and 4 are plan views of knives before they are united, showing slots. Fig. 5 is a perspective view of 25 slotted journal. Fig. 6 is a cross-section, showing cutter with more than two leaves. Figs. 7 and 9 are plan views of cutter-blanks slotted beyond their centers. Fig. 8 is a plan of cutter-blank, slotted at each end. Fig. 10 is 30 a plan of cutter-blank with journals forged thereon.

Similar letters of reference indicate like parts in the several figures.

The revolving cutters of lawn-mowers heretofore made have employed cast or malleable iron in their construction. The cast-iron being brittle and the malleable iron expensive as to 35 material and fitting, neither of them are particularly well suited for the purpose. Besides, such construction renders the cutter unnecessarily heavy. This cast-iron has been employed in some instances in the shape of spiders secured to a central shaft, to the extremities of which the steel knives have been 40 riveted. In other instances the cutter has been composed of a cast-iron frame having the knives secured to its spiral outlines, and in another instance the cutter is cast solid, with radiating spirally-curved wings, to the edges 45 of which are fixed the steel blades. This latter form of cutter, when a number of wings

are desired, is exceedingly difficult to cast, since it cannot be drawn from the mold excepting when patterns of peculiar construction are used. All of the aforesaid cutters are objectionable because either of their weight, brittleness, expense of manufacture, or lack of stiffness, and in every instance the steel blade has necessarily been riveted, bolted, or keyed to the cast or other metal. 55

In my cutter, which is the subject of the present invention, these objections are obviated, and a strong, light, and easily-made cutter is produced, and one that can be sharpened or ground down to any reasonable extent, it 60 being made of steel throughout, whereas in the cutters consisting of steel knives combined with cast or malleable iron the knives will speedily become, by sharpening, reduced to such an extent as to require their renewal. 65

In making my cutter I take two or more, plates, of steel or any other suitable material A of the required thickness and length, and form in each plate a slot, *a*, extending in the direction of its length. The plates A having 70 been bent to the usual spiral curve, (either before or after they are slotted,) the slotted part of one plate is inserted into the slotted portion of another plate or plates, so that the plates may be at right angles or at some other convenient angle to each other, in which position they are held in any suitable manner. Journals B may be forged on the ends of the plates A or be riveted thereon, or the journals may be made with angular openings *c* in one of 75 their ends to correspond with the angular positions of the ends of the plates, and these journals may be shrunk onto the ends of the plates or riveted to the ends of the blades of the cutter. Now, with the exception of sharpening and fitting the journal-bearings my cutter is completed and ready to be attached to the other portions of the lawn-mower. 80

The cutter is caused to revolve by the usual rollers, wheels or gears, endless chain or band, 85 or otherwise, as may be desired.

This form of cutter may also be employed in the construction of hay and chaff cutters and other agricultural machines, and the economy arising from its manufacture will be apparent 90 when the small number of its parts and the simplicity of its construction are considered. 100

Having now described my invention, what I claim as new, and desire to secure by Letters Patent, is—

1. A revolving cutter for lawn-mowers, composed of longitudinally-slotted blades fitted together, as shown and described, and combined with the journals B, applied at opposite axial ends of the blades to hold them together and permit the rotation of the cutter, substantially as specified.
2. In a revolving cutter for lawn-mowers,

two or more slotted plates fixed at suitable angles to each other, in combination with necessary journals, wherein or upon are received and fixed the ends of the plates, and whereby the cutter may revolve, as and for the purpose described.

J. W. HOBSON.
